Application October 18, 1956, Serial No. 616,765

2 Claims. (Cl. 250—27)

The present invention relates to an improved bistable device capable of being set to a first or second stable state.

More particularly, the present invention relates to that class of bistable devices in which a number of tubes are cascaded and a feedback circuit provided so as to form a closed circuit. Each tube is designed to assume a stable condition of maximum or minimum conductivity which may be referred to as an On and Off condition, respectively. The condition of each tube is determined by the condition of the preceding tube so that the condition of one tube will determine the conditions of all tubes. Once set in a given condition, each tube will remain in that condition until some external stimulus is applied. An example of this type circuit is shown in the patent to E. S. Hughes, Jr., Patent No. 2,628,309.

In prior devices, such as shown in Hughes, the circuit comprises three tubes, two inverters and a cathode follower. The plate of the first inverter is connected to the grid of the second inverter, the plate of the second inverter is connected to the grid of the cathode follower and the cathode of the cathode follower is connected to an output circuit in addition to providing a connection back to the grid of the first inverter. In circuits of this type, where the condition of one tube will determine the conditions of all tubes because of the closed circuit arrangement, it is apparent that the speed of operation will depend upon the time it takes for all tubes to reach a stable condition. Where the output of such a device is loaded with a large amount of capacitance, the time it takes for the cathode follower to discharge this capacitance will limit the speed of response of the device since the first inverter will depend for operation upon the cathode voltage of the cathode follower.

If the device is one of a plurality in a ring circuit driven by a source of ring drive pulses, failure to assume an On position before the next drive pulse will cause failure of the ring. This is caused by the fact that succeeding devices are operated by a pulse from a preceding device when the preceding device goes from an On to an Off position. If the preceding device does not assume an On position, there will be no pulse to operate the succeeding device. An On position is defined as a situation in which the cathode follower conducts heavily and an Off position is defined as a situation in which the cathode follower is only slightly conducting.

Since ring circuits in computer applications characteristically work over long lines, there is a large amount of capacitance associated with the output of each device in the circuit.

It is therefore an object of this invention to provide an improved bistable device.

It is a further object of this invention to provide a bistable device relatively insensitive to load variations.

It is another object of this invention to provide a bistable device which operates at a higher frequency than those previously known.

Other objects of the invention will be pointed out in

2

the following description and claims and illustrated in the accompanying drawing, which discloses, by way of an example, the principle of the invention and the best mode, which has been contemplated, of applying that principle.

In the drawing:

The circuit shown in the figure consists of three tubes V₁, V₂ and V₃. V₁ and V₂ function as inverters and V₃ functions as a cathode follower. The normal condition of this circuit, which shall be referred to as an Off condition, is where tube V₁ is nonconducting, tube V₂ is conducting and tube V₃ is only slightly conducting. The output taken from the cathode of V₃ at this time will be at some negative potential level. The On condition of this circuit is where V₁ is conducting, V₂ is nonconducting and V₃ is conducting heavily. The output at this time will be at some positive potential level.

The circuit is shown as it would be connected into a ring circuit with an output to the next stage taken from tubes V₂ and V₃. This output would be connected to a terminal in a subsequent stage labeled "Set" as shown in the instant stage.

A "Reset" for manually switching from an On to an Off condition is shown connected to the input of tube V₁. An advance pulse input is shown which would be connected to a ring drive for switching the stage from On to Off where the circuit is used as a stage of a ring.

With tube V₁ nonconducting, the plate of said tube assumes the potential at point 18. The plate of tube V₁ is connected to the grid of tube V₂. The positive potential at the plate of V₁ is sufficient to overcome the negative bias applied to V₂ and V₂ conducts.

The positive voltage at 9 is connected through a large resistor 10, through diode 13 to the cathode of V₃, through resistor 41 to the plate of V₂. With V₂ conducting, current will flow from 9 through V₂. With current flow through resistor 41, the grid of tube V₃ will be at a more negative potential than the cathode of V₃ and V₃ will therefore be biased near cutoff. Resistor 10 is very large compared to the resistor 41 and the resistor 35 in the cathode circuit of V₂ so that substantially the entire voltage drop between voltage source 9 and the cathode voltage V₂ appears across resistor 10. This voltage drop brings the point 8 below ground potential and keeps V₁ cut off so that the circuit will be stable in the Off position. With V₂ conducting and V₃ only slightly conducting, the output will be at a negative potential. The diode 44 prevents the line from going too far negative.

To operate the circuit to an On condition, a negative pulse is applied at terminal 26 labeled "Set." This pulse is connected to the grid of tube V₂ through a voltage dividing network composed of resistors 21, 23 and capacitors 20, 22.

This negative pulse drives the grid of tube V₂ below cutoff and the tube V₂ is operated to its nonconducting condition. With tube V₂ nonconducting, the potential at point 38 will be the same as that for the cathode of tube V₃ (no current flow through resistor 41) and tube V₃ will conduct heavily. With tube V₃ conducting, the cathode of V₃ will rise to a potential high enough to prevent too large a voltage drop across resistor 10 and the tube V₁ will be biased to conduction. With tube V₁ conducting, the plate of tube V₁ is approximately at ground potential. V₂ was cut off by the pulse on terminal 26 and, since V₂ is normally biased to cutoff by source 32, the presence of ground potential on the plate of tube V₁ is not sufficient to make tube V₂ conduct. The circuit is now in a stable On condition and will remain in this condition until it is reset to an Off condition by a negative pulse on the reset or advance pulse line.

The output of this circuit is taken from a parallel combination of the outputs of tubes V_2 and V_3 . From the figure it can be seen that the plate of tube V_2 is connected through a resistor 41 to the output terminal and the cathode of tube V_3 is connected directly to the output terminal. Any output pulse therefore will be a direct function of the outputs of tubes V_2 and V_3 .

At this point it may be well to digress for a moment and consider the behavior of a cathode follower when driving a load. When a cathode follower conducts, current will flow from the plate to the cathode and then to the load. From this it can be seen that a cathode follower will deliver a large amount of power (current) at the positive excursion of an output pulse. When the cathode follower is biased near cutoff, current flow is from the line into the cathode circuit of the cathode follower. When the output contains considerable capacitance, as it does where these devices are used, the capacitance must discharge through the cathode resistor and the load resistance in parallel (shown in broken lines in the figure). In an R-C circuit, the voltage decays exponentially in accordance with the circuit constants. One way to help this condition is to greatly lower the value of the cathode resistor but this necessitates either a larger tube with a higher plate dissipation or tubes in parallel.

Since the cathode voltage will decay exponentially in accordance with the capacity of the line and the cathode resistor, it will take a given amount of time before the voltage reaches some predetermined level. If the instant device is used in a ring circuit driven at some predetermined frequency, it can be seen that a failure of one stage to change condition before the next advance pulse arrives will cause the ring to fail.

A plate driver, when connected to an output, functions when conducting to accept current from the output line. When nonconducting, the plate driver is effectively an open circuit and current to the line would be from the plate supply. Therefore, for a negative excursion of an output pulse, i.e., plate driver conducting, any capacitance of the line would be discharged through the plate driver, while for a positive excursion, i.e., plate driver nonconducting, current would be from the plate supply and the plate driver would have the same disadvantages as the cathode follower would for a negative excursion.

To make the device of the figure more independent of load variations with regard to changes in condition of the device, a plate driver and a cathode follower have been combined to furnish an output pulse which will turn the device On or Off in a faster time than previously known.

As previously stated, a plate driver such as V_2 will have optimum operation when generating the negative excursion of an output pulse taken across the plate since the circuit is through the tube V_2 to the cathode circuit where the resistor 35 has a small resistance. A cathode follower such as V_3 will have optimum operation when generating the positive excursion of an output pulse taken across the cathode since the circuit is through the tube V_3 from the plate supply where the resistor 40 has a small resistance. Equally important is the fact that a cathode follower will present a low impedance to the line between pulses and minimize spurious "Crosstalk." Therefore, in using a plate drive such as V_2 and a cathode follower such as V_3 in combination, an optimum output waveform is achieved.

From the foregoing analysis it can be seen that the tubes of the output circuit determine the sharpness of the output pulse. Since the time which it takes for the entire circuit to assume a stable state is dependent upon the time it takes for the output pulse to assume a particular voltage level, it can be seen that the frequency at which the circuit will respond is directly dependent upon the output waveform. With the circuit as shown,

the improvement in output waveform has materially increased the response time.

To further improve the response time of the present circuit, a capacitor 14 has been inserted in the feedback circuit. The capacitor allows the grid of tube V_1 to follow the feedback voltage from the output more quickly than by merely using the diode.

To prevent the negative-going pulse at terminal 26 from driving the grid of V_2 below cutoff and consequently increasing the time that it takes for the grid to approach the normal voltage for cutoff, a connection was made to the cathode of V_2 to the point 25 of the voltage dividing network. A diode 29 isolates the network from the cathode potential at times when there is no input pulse at 26. For a large negative pulse, the diode conducts and keeps the point 25 at a predetermined level below the cathode voltage dependent upon the resistor 35.

The diodes 33 and 44 are used to prevent the output waveform from going too high or too low, i.e., for clipping.

The diodes 11 and 12 form an Or circuit wherein terminals 4 and 5 are maintained at a potential high enough to prevent current flow from source 9 through diodes 11 and 12. When it is desired to reset or advance the circuit from an On to an Off condition, a negative pulse is supplied. The resistor 10 will then permit the voltage at the grid of tube V_1 to drop below cutoff and the circuit will be turned Off.

While there have been shown and described and pointed out the fundamental novel features of the invention as applied to a preferred embodiment, it will be understood that various omissions and substitutions and changes in the form and details of the device illustrated and in its operation may be made by those skilled in the art, without departing from the spirit of the invention. It is the intention, therefore, to be limited only as indicated by the scope of the following claims.

What is claimed is:

1. A bistable device comprising a first, second and third electron tube, each tube containing at least a plate, grid and cathode, a first and second series connected parallel resistance capacitance section connecting the plate of said first tube to the grid of said second tube, means connecting the cathode of said second tube to a junction between said first and second series connected sections whereby the voltage at said junction will be a function of the voltage of said cathode, means connecting the plate of the second tube to the grid of said third tube, means connecting the cathode of said third tube to the grid of said first tube whereby the conduction of any one tube will determine the conduction of all tubes to set said device in either a first or second stable state, an input connected to the junction between said first and second sections for coupling a pulse to the grid of said second tube to set said device in one of its stable states and an output from said device connected from the cathode of said third tube and the plate of said second tube.

2. The apparatus of claim 1 wherein said means connecting the cathode of said third tube to the grid of said first tube comprises a parallel combination of a diode and a capacitor whereby said first tube is made more responsive to the change in condition of said third tube.
